(57) **CLAIM**

I claim, the ornamental design for a side plate, as shown and described.

DESCRIPTION

FIG. 1 is a perspective view of a side plate, showing our new design;

FIG. 2 is a front view of the embodiment shown in FIG. 1;
FIG. 3 is a back view of the embodiment shown in FIG. 1;
FIG. 4 is a side view of the embodiment shown in FIG. 1;
FIG. 5 is another view of the embodiment shown in FIG. 1;
FIG. 6 is a top plan view of the embodiment shown in FIG. 1;

FIG. 7 is a bottom view of the embodiment shown in FIG. 1; and,

FIG. 8 is a perspective view of a side plate of FIG. 1 in a conga drum environment.

The broken lines are directed to environmental subject matter only and form no part of the claimed design.

1 Claim, 6 Drawing Sheets
